CLAIM

The ornamental design for a cleaning brush, as shown and
described.

DESCRIPTION

FIG. 1 is an isometric view of a cleaning brush according to
the present disclosure;

FIG. 2 is a front view of the cleaning brush of FIG. 1;

FIG. 3 is a right view of the cleaning brush of FIG. 1;

FIG. 4 is a back view of the cleaning brush of FIG. 1;

FIG. 5 is a top view of the cleaning brush of FIG. 1;

FIG. 6 is a left view of the cleaning brush of FIG. 1; and,

FIG. 7 is a bottom view of the cleaning brush of FIG. 1.

Broken lines and unshaded portions contained within broken
lines depict portions of the cleaning brush that are environ-
mentally illustrative only and form no part of the claimed
design.

1 Claim, 7 Drawing Sheets
